R. H. HARRIS,
DRILLING APPLIANCE,
APPLICATION FILED MAY 12, 1917.

1,250,450.

Patented Dec. 18, 1917.

Inventor:

Richard Henry Harris,
By J. Walter Fowler,
atty

UNITED STATES PATENT OFFICE.

RICHARD HENRY HARRIS, OF LONDON, ENGLAND, ASSIGNOR TO FASTNUT, LIMITED, OF LONDON, ENGLAND, A CORPORATION OF ENGLAND.

DRILLING APPLIANCE.

1,250,450.

Specification of Letters Patent.

Patented Dec. 18, 1917.

Application filed May 12, 1917. Serial No. 168,297.

To all whom it may concern:

Be it known that I, RICHARD HENRY HARRIS, of Salisbury, Southern Rhodesia, a subject of the King of England, and at present residing at London, England, have invented certain new and useful Improvements in Drilling Appliances, of which the following is a specification.

This invention has for its object to provide improved appliances for enabling holes of various cross-sections to be drilled.

According to this invention, the drilling appliance comprises three parts or members placed end to end, one end part being adapted to be received by the chuck and the other end part being adapted to receive or control the drill, the intermediate part being connected to the end parts by coupling connections which allow of relative lateral displacement of the three parts or members. For this purpose I may employ groove and tongue connections between the three parts. The end parts or members are held against or pressed on to the intermediate part by elastic or resilient means. The drill may be guided by a die or templet in its lateral movement relatively to the material which is being drilled.

By the use of the appliance, holes of triangular, square or polygonal cross-section can be readily and accurately drilled.

In order that the invention may be clearly understood and readily carried into effect one embodiment of the invention will now be described with reference to the accompanying drawings, in which:—

Figures 1 and 2 are elevations of the drill-holding appliance, the two views being taken respectively in two directions at right angles, and Fig. 2 being in section.

Fig. 3 is an under plan view of the appliance.

Fig. 4 is a top plan view with certain parts displaced as occurs in the use of the appliance.

Figs. 5 and 6 are sections on the lines 5—5 and 6—6 respectively in Fig. 2.

Figs. 7, 8 and 9 are an elevation and end views respectively of a drill suitable for use in drilling a hole of square cross-section.

Figs. 10 and 11 are a plan and a side elevation respectively of the die used in drilling a hole of square cross-section.

Figs. 12 and 13 are an elevation and an

end view of a drill suitable for use in drilling a hole of hexagonal cross-section, and Fig. 14 is a plan of the die used in drilling a hole of hexagonal cross-section.

Fig. 15 shows a tapered arrangement of one of the parts of the drilling appliance.

The appliance comprises three cylindrical parts A, B and C, which are bored centrally as shown. The part A is inserted in the chuck of the drilling or like machine. Fixed in the bore of the part C is a stem C' which passes upward through the parts B and A and is screw-threaded at the top to receive a nut D. A spring E surrounds the top of the stem C' its ends abutting against the nut D and a washer F resting on the top of the part A. The shank of the drill is adapted to be inserted in the lower end of the bore C² of the part C and is held in position by a set-screw C³. The part A is provided with two tongues or projections A' which fit into and can laterally slide in corresponding grooves in the part B. The part B is also provided with two tongues B' which fit into and can laterally slide in corresponding grooves in the part C. The

grooves in the part B which receive the tongues A' are on a diameter at right angles to the diameter containing the tongues B'. Consequently the part C can be displaced in one direction relatively to the part B and the part B can be displaced relatively to the part A in a direction at right angles to the first mentioned direction. In Fig. 4 the parts A, B and C are shown out of alignment. The amount of relative movement of the parts A, B and C is limited by the clearance between the outside of the stem C' and the inner walls of the parts A and B.

In employing the appliance, the part A is fixed in the chuck of the drilling machine and the drill is fixed in the part C, as hereinbefore mentioned. A die or templet in the form of a thick hardened plate, in which a hole has been cut of the same cross-section as that of the hole to be drilled, is clamped to the material to be drilled. The drill which is of suitable shape for cutting the required hole is fed through the die and the hole is drilled in the ordinary manner.

Though the groove and tongue connections between the parts A, B and C permit of the relative lateral movement of these parts as hereinbefore described, these connections

provide an effective method of transmitting the rotary movement of the chuck to the drill and also of preventing the axis of the drill from being displaced angularly.

5 In Figs. 7, 8 and 9, there is shown a drill and in Figs. 10 and 11 a die suitable for use in drilling a hole of square cross-section. The drill G has a shank G' and three cutting edges G². The outer ends of the three cutting edges are at the vertices of an equilateral triangle and each side of the triangle is approximately equal in length to the side of the square hole to be drilled. The die H is provided with a square hole H'.

15 For drilling a hole of hexagonal cross-section, a drill J having a shank J' and five cutting edges as shown Figs. 12 and 13 may be employed together with a die K as shown in Fig. 14. In drilling a hole of any polygonal cross-section, a drill having a number of radical cutting edges at equal angles apart is preferably employed, the angle between two contiguous sides of the polygon formed by the outer ends of the edges being less than the angle between two contiguous sides 25 of the polygonal hole to be drilled.

The part A may have a cylindrical outer surface as shown in Figs. 1 and 2 or its outer surface may be tapered or of any other suitable shape to fit the chuck. In 30 Fig. 15 the part A is tapered. Instead of fitting the part A directly into the chuck, the part A may be fixed into a sleeve or holder which is itself received by the chuck. 35 Such arrangement of sleeve or holder will be easily understood by any one familiar with the art.

Instead of, or in addition to, employing an appliance as hereinbefore described for 40 holding the drill, such an appliance may obviously be employed in connection with the supporting structure or holder for the material to be drilled.

Having thus described my invention what 45 I claim as such and desire to secure by Letters Patent is:—

1. A drilling appliance for enabling holes of various cross-sections to be drilled, comprising a plurality of members connected 50 together and arranged in succession, said connected members adapted to be arranged between the chuck and drill, coupling connections between the three members, said coupling connections allowing lateral displacement of the members relatively to one another, and resilient means for holding the end members up to the intermediate member.

2. A drilling appliance for enabling holes of various cross-sections to be drilled, comprising three members placed end to end, one end member being adapted to be controlled by a rotating driver and the other end member being adapted to control the drill, the intermediate member being connected with the end members by devices

which allow of laterally sliding movement, and elastic means for holding the end members up to the intermediate member.

3. A drilling appliance for enabling holes of various cross-sections to be drilled, comprising three members arranged end to end, one end member being adapted to be received by the chuck of the rotating device and the other end member being adapted to receive the drill, the intermediate member being connected to the end members by groove and tongue connections, and the end members being pressed on the intermediate member by resilient means.

4. A drilling appliance for enabling holes of various cross-sections to be drilled, comprising three members arranged end to end, one end member being engageable by the chuck of the driver and the other end member being adapted to receive and control the drill shank, the intermediate member being connected to each of the end members by grooves and tongues, the said groove and tongue connections between the intermediate member and one end member being at 90 right angles to the groove and tongue connections between the intermediate member and the other end member, and resilient means for holding the end members pressed against the intermediate member.

5. A drilling appliance for enabling holes of various cross-sections to be drilled, comprising three hollow parts placed end to end, one said end part being receivable by the chuck and the opposite end part adapted to receive the drill, the intermediate part being connected to the end parts by sets of coupling connections which will allow of lateral displacement of the parts, the one set of coupling connections being at right angles to the other set, and a spring-fitted connection being the end parts passing through the intermediate part and serving to hold the outer parts against the intermediate part, in combination with a die having a hole of the cross-section to be drilled and through which the die passes.

6. The employment for drilling holes of various cross-sections, of a drilling appliance comprising three parts placed end to end, the intermediate part being connected with the end parts by coupling connections which allow of relative lateral displacement of the three parts, resilient means for holding the end parts up to the intermediate member, of a die of the same cross-section as that of the hole to be drilled, and of a drill fitted to the drilling appliance and passed through said die.

7. As a means for drilling holes of various cross-sections, the combination of a holder comprising three parts arranged end to end and having coupling connections which allow of lateral displacement between the said three parts, the end parts being held

against the intermediate part in a resilient manner, of a drill adapted to be fitted to and controlled by one of said end members, and of a device shaped to the hole to be drilled, and through which the drill is passed, for guiding the drill in its lateral movements.

8. As a means for drilling holes of various cross-sections, the use in combination of a holder comprising three parts placed end to end with the outer parts pressed against the median part and having coupling connec-

tions between said parts to allow of lateral displacement of said parts, of a drill, and of a guiding die shaped to the cross-section of the hole to be bored, said drill being passed through said die.

In testimony whereof I affix my signature in presence of two witnesses.

RICHARD HENRY HARRIS.
